UNITED STATES PATENT OFFICE.

BEN K. FORD, OF DETROIT, MICHIGAN, ASSIGNOR TO DETROIT CAN COMPANY, OF DETROIT, MICHIGAN, A CORPORATION OF NEW JERSEY.

RECEPTACLE.

1,141,534.

Specification of Letters Patent.

Patented June 1, 1915.

Application filed June 15, 1912. Serial No. 703,894.

To all whom it may concern:

Be it known that I, BEN K. FORD, a citizen of the United States, residing in Detroit, in the county of Wayne and State of Michigan, have invented a new and useful Improvement in Receptacles, of which the following is a specification.

This invention relates to improvements in receptacles, and more particularly to that type of receptacles or packages used for dispensing tobacco.

The object of the invention is to provide a form of tobacco box or package adapted for tobacco or other materials, having a hinged cover, and which will be adapted to prevent spilling or waste of the contents while being discharged from the package, and in which the cover will stay in place without the use of catches or other devices, when the cover is closed.

Another object of the invention is to provide a package of the type above outlined, which will be simple and composed of few parts and exceedingly cheap to manufacture, and one in which the hinge pintles are preferably formed integrally with the metallic cover.

The invention furthermore consists in the improvements in the parts and devices and novel combinations of parts and devices herein shown, described or claimed.

In the drawing forming a part of this specification, Figure 1 is a side elevation of a receptacle embodying my improvements. Fig. 2 is a vertical section of the structure shown in Fig. 1, showing in dotted lines the position assumed by the cover when the contents are being discharged from the package. Fig. 3 is a partial, sectional view, taken on the line 3—3 of Fig. 1, looking in the direction of the arrows, and Fig. 4 is a transverse section, taken on the line 4—4 of Fig. 1.

In the drawing, A denotes the main or body portion of the receptacle or package, the body A being preferably formed of paper, or other material having similar properties, wound in convolute layers, and, as shown, being of ovaliform shape and having a metallic bottom 11 seamed thereto. The upper edge of the body A at one end thereof is cut away, as shown at 12, and on each side at points adjacent this cut away portion, the body may be provided with

diagonally disposed slots 13, 13, which extend only partially through the upper side walls of the body and which are adapted to receive the hinge pintles 14, 14, formed integrally with the metallic cover B, said pintles being formed by striking up the metal of the flange 15 of the cover in a well known manner. A portion of the depending flange 15 is cut away, as shown at 16, at the end opposite to that where the cut out portion 12 of the body is disposed. The cover B is placed on the body A by squeezing the side walls of the body inwardly slightly, sufficient to clear the hinge pintles 14, 14, and after the cover is in place, the side walls of the body are allowed to spring out and the hinge pintles will then engage in the slots 13, 13. As clearly shown in the drawing, the flange 15 of the cover snugly fits the body, while the cover is in a closed position, and will thus be retained in proper place after the cover is closed. When it is desired to pour out tobacco or other materials from the receptacle, the user first places his finger or thumb on the end of the cover in the manner as shown in dotted line in Fig. 1, and depresses this end of the cover, thereby swinging the cover up into the position shown in dotted line in Fig. 2, and it will be noted that the cover has, in addition to the pivotal movement, a slight bodily movement relatively to the body A, due to the hinge pintles sliding in the slots on the sides of the body. As will be obvious, the cover can be opened only to a slight extent and will serve, in conjunction with the rounded end of the body, to guide or direct the tobacco into the pipe or other article while the tobacco is being poured, thus preventing any spilling or waste, which has been an objection to tobacco receptacles as heretofore constructed. In closing the cover, the user places his finger or thumb on the cover in the manner shown in dotted line in Fig. 2, and by depressing the cover and giving the same a slight bodily movement presses the cover so that the same snaps onto the body and will be held in closed position, as shown in Fig. 1.

Although slots 13 are shown as formed in the side walls of the body A, in the drawing, in actual practice it is found that the hinge pintles 14 of the metallic cover, after having been snapped into place, will, of

their own accord, wear or tear out a groove after the cover has been opened once or twice.

Although I have described the preferred form of my improvements, it will be obvious that changes may be made in the details of construction without departing from the spirit of the invention, and all such changes are contemplated as fall within the scope of 10 the claims appended hereto.

I claim:

1. A receptacle of the character described comprising, in combination, a body member having an open top and outwardly resilient 15 sides, and a cover having at its sides a pair of opposite inwardly extending hinge pintles which enter elongated recesses formed in the said sides of the body; substantially as specified.
2. A receptacle of the character described, comprising, in combination: a body member having relatively stiff outwardly resilient side walls composed of fibrous material, said body member having an open top; and 25 a metallic cover having at its sides inwardly extending metallic pintles formed by striking up the metal of the cover, said pintles being adapted to wear and form elongated pivot slots in the side walls, said cover 30 being bodily movable with respect to said body member; substantially as specified.
3. A receptacle having an ovaliformed body the upper edge of which is cut away at one end of the body, combined with a flanged 35 cover the flange of which closely embraces the upper end of the body and is cut away

at the end of the cover remote from the said cut away portion of the body, whereby the bodily movement of the cover toward the cut away portion of the body is permitted 40 and a pouring opening is formed.

4. A receptacle of the character described comprising, in combination, an ovaliformed body member having its side walls composed of resilient material formed with longitudinally extending slots, and a metallic cover hinged thereto, said metallic cover having a depending flange adapted to fit over the body when in closed position and having hinge pintles formed integrally therewith and adapted to take into said longitudinally extending slots in the side walls of the body member.

5. A receptacle of the character described comprising, in combination, an ovaliformed body member having outwardly resilient side walls, formed with elongated pivot bearing slots, and a metallic cover hinged thereto, said metallic cover having a depending flange adapted to fit the body and having hinge pintles formed integrally therewith and adapted to take into the said slots in the side walls of the body member, the upper edge of the body member being cut away at the end adjacent the hinge pintles and the flange of the cover being cut away at the opposite end.

BEN K. FORD.
